US00D994704S

(12) **United States Design Patent** (10) **Patent No.:** **US D994,704 S**
Yum et al. (45) **Date of Patent:** **** Aug. 8, 2023**

(54) **DISPLAY SCREEN WITH GRAPHICAL USER INTERFACE**

(71) Applicant: **Airbnb, Inc.**, San Francisco, CA (US)

(72) Inventors: **John Yum**, San Francisco, CA (US); **Jared Robert Fancy**, San Francisco, CA (US); **Jarrett Michael Carr**, Austin, TX (US); **Derek Li Chan**, San Francisco, CA (US)

(73) Assignee: **AIRBNB, INC.**, San Francisco, CA (US)

(**) Term: **15 Years**

(21) Appl. No.: **29/867,298**

(22) Filed: **Oct. 19, 2022**

Related U.S. Application Data

(63) Continuation of application No. 29/784,975, filed on May 22, 2021, now Pat. No. Des. 970,530.

(57) **CLAIM**

The ornamental design for a display screen with graphical user interface, as shown and described.

DESCRIPTION

The FIGURE is a front view of a display screen with a graphical user interface showing our new design.

The peripheral dash-dot-dash lines illustrate a display screen or portion thereof and form no part of the claimed design. The broken lines surrounding the white text illustrate interior boundaries of the claimed design and the broken lines and the white text therein form no part of the claimed design. The remaining broken lines illustrate features that form no part of the claimed design.

1 Claim, 1 Drawing Sheet
